UNITED STATES PATENT OFFICE

2,396,811

AIRPLANE PROPELLER

James E. Bathras, Portland, Maine

Application December 10, 1943, Serial No. 513,760

1 Claim. (Cl. 170—159)

This invention relates to an airplane propeller, and particularly to the formation of the blades thereof.

Airplane propellers are of relatively large size or have long blades, and they ordinarily create a loud humming noise when operating at high speed. Also, with the ordinary airplane propeller, there is noticeable loss of efficiency at the tip portion of the blade, due to centrifugal slippage.

The primary objects of the present invention, therefore, are to provide an airplane propeller which, through its particular blade formation, will be relatively quiet when operating at high speed, as well as highly efficient, and which will nullify tip loss resulting from centrifugal slippage, by causing a centripetal movement of air, through a particular arrangement and form of fin on the tip portion of the blade.

A specific object of the invention is to increase the efficiency of the propeller and bring about quiet operation through a particular fin formation on the trailing edge of the blade, respectively along the major intermediate portion of the trailing edge and on the trailing edge at the tip of the blade.

The present invention consists in the novel form, combination and arrangement of features and parts hereinafter more fully described, shown in the accompanying drawing and claimed.

In the drawing, wherein like reference characters indicate corresponding parts throughout the several views:

Figure 1 is a rear elevational view of an airplane propeller constructed in accordance with the present invention.

Figure 2 is a transverse section taken on the line 2—2 of Figure 1, and

Figure 3 is a section taken on line 3—3 of Figure 1.

Referring in detail to the drawing, I have shown an airplane propeller having two blades 5 of similar form and extending from opposite sides of a central hub 6. Each blade has a pressure side 7 and a non-pressure side 8. The leading edge is indicated at 9, and the trailing edge at 10. As usual, the blades are disposed at a desirable pitch or angle to the axis of rotation, which may be on the line 11. The direction of rotation is indicated by the arrows 12 and the direction of air movement by the arrows 13. The line 14 is

the plane of rotation of the trailing edge and the line 15 the plane of rotation of the leading edge.

As shown clearly in Figure 1, the leading edge 9 is substantially parallel to a line extending longitudinally of the blades and through the axis of rotation, while the trailing edge is bowed out considerably to give sufficient blade area at the different sections. In accordance with the present invention, a fin 16 is provided to extend along the major intermediate portion of the trailing edge 10, and this fin is turned outwardly and forwardly toward the direction of travel of the airplane, as shown in Figure 2. Another smaller fin 17 is provided on the trailing edge at the tip end portion of the blade, said fin 17 being turned outwardly and rearwardly in the direction of air flow or movement caused by the propeller. The main or body portion of the blade merges with the fins on curves. As shown, the blade is relatively thick adjacent the nose or leading edge and tapers thinner toward the trailing edge, but the cross sectional or airfoil shape of the blade may vary to some extent. The effect of fin 16 is to lead the air from the pressure side outwardly and forwardly for gradually diminishing turbulence and thereby resulting in a considerable reduction in the loud humming noise ordinarily caused by an airplane propeller when operating at high speed. The fin 17 causes a centripetal movement of air and thereby nullifies tip loss from centrifugal slippage.

Although a specific embodiment of the invention is illustrated and described, it will be understood that various changes may be made within the scope of the invention as claimed.

What I claim as new is:

An airplane propeller adapted to be rotated about an axis for displacing air and comprising a hub, a plurality of blades of similar form extending from the hub and disposed at an angle to the axis of rotation, each of said blades having an outwardly bowed trailing edge, a fin curved forwardly from the major intermediate portion of the trailing edge of each blade, and having an outwardly bowed trailing edge, and a second fin on the trailing edge at the tip end of each blade, the last named fin being curved rearwardly and having an outwardly bowed trailing edge.

JAMES E. BATHRAS.
